United States Patent Office.

JOHN PROTIN, OF NEW YORK, N. Y., ASSIGNOR TO JAMES L. HOWARD AND COMPANY, OF HARTFORD, CONNECTICUT.

Design No. 3,523, dated June 1, 1869.

DESIGN FOR A CAR-BRACKET.

The Schedule referred to in these Letters Patent and making part of the same.

To all whom it may concern:

Be it known that I, JOHN PROTIN, of New York, in the county of New York, and State of New York, have originated and designed a new Pattern for a Car-Bracket, of which the following is a full, clear, and exact description, reference being had to the accompanying drawing, making a part of this specification, and to the letters of reference marked thereon.

My design is intended for the brackets forming the ends of the bracket-baskets now used in passenger-railway cars for the purpose of depositing the lighter articles of baggage.

My design consists in the peculiar form and arrangement of curves and ornaments, shown in the accompanying drawing.

a and *b* are the outside curves, between which are placed the ornamental portions, *c d*.

e is a circular post, outside of *b*, which is generally used for holding umbrellas.

The curved rib *b* is furnished with circular bosses *f*, where the ends of the longitudinal wires of the basket are inserted.

Claim.

What I claim as my invention, and desire to secure by Letters Patent of the United States, is—

The design for a car-bracket, herein set forth.

JOHN PROTIN.
